(57) **CLAIM**

The ornamental design for a band for a wearable device, as shown and described.

DESCRIPTION

FIG. 1 is a top perspective view of a band for a wearable device;

FIG. 2 is bottom perspective view thereof;

FIG. 3 is a left-side view thereof;

FIG. 4 is a right-side view thereof;

FIG. 5 is a front view thereof;

FIG. 6 is a back view thereof;

FIG. 7 is a top view thereof;

FIG. 8 is a bottom view thereof; and,

FIG. 9 is a top perspective view of the band for a wearable device of FIG. 1, shown in a position of use.

The broken lines in the drawings represent portions of the band for a wearable device and form no part of the claimed design. The other broken lines in FIG. 9 showing a wearable device represent environmental subject matter only and form no part of the claimed design.

1 Claim, 9 Drawing Sheets
